(57) **CLAIM**

The ornamental design for a retractable lighted keyring magnifier, as shown and described.

DESCRIPTION

FIG. 1 is a perspective view of a retractable lighted keyring magnifier showing our new design with the magnifier retracted;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view of the retractable lighted keyring magnifier showing our new design with the magnifier extended;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof; and,

FIG. 14 is a bottom plan view thereof.

The keychain depicted by means of broken lines in the drawings is shown for illustrative purposes only and forms no part of the claimed design.
